United States Patent Office

Des. 177,872
Patented May 29, 1956

177,872

MITTEN

Marjorie E. McCarthy, San Francisco, Calif.

Application December 5, 1955, Serial No. 39,165

Term of patent 14 years

(Cl. D3—11)

Fig. 1 is a plan view of one side of a mitten showing my new design, the side opposite thereto being similar in appearance; and

Fig. 2 is an edge view thereof as seen from line 2—2 of Fig. 1.

The opposite side of the mitten is the same in appearance.

I claim:

The ornamental design for a mitten, as shown and described.
